(57) **CLAIM**

The ornamental design for artificial twig branches with lights as shown and described.

DESCRIPTION

FIG. 1 is a perspective view of artificial twig branches with lights showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the artificial twig branches with lights, shown in use with light strings surrounding;

FIG. 10 is an enlarged view of portion 10 shown in FIG. 1; and,

FIG. 11 is an enlarged view of portion 11 shown in FIG. 9. The dash-dash broken lines in the drawings depict portions of the artificial twig branches with lights that form no part of the claimed design. The dot-dash broken lines represent boundaries of the enlarged portions and form no part of the claimed design.

1 Claim, 11 Drawing Sheets
